UNITED STATES PATENT OFFICE.

EGBERT H. GOLD, OF CHICAGO, ILLINOIS.

VENTILATOR FOR RAILWAY-CARS.

1,105,645.

Specification of Letters Patent.

Patented Aug. 4, 1914.

Application filed March 28, 1912. Serial No. 686,775.

To all whom it may concern:

Be it known that I, EGBERT H. GOLD, a citizen of the United States, residing at Chicago, in the county of Cook and State 5 of Illinois, have invented certain new and useful Improvements in Ventilators for Railway-Cars, of which the following is a specification.

My invention relates to ventilators for 10 railway cars of the sort which are arranged outside of the car, usually on the side wall of the clear story, and are so formed as to produce a draft, induced by the movement of the car, which operates to suck the foul 15 air out of the car.

The invention has for one of its objects 20 to provide an improvement upon or an attachment for ventilators of this type which will prevent or diminish back draft of outside air into the car. Such back draft into 25 the car is likely to occur when the car is standing still and the wind is blowing against the side of the car. The ventilators of this type which have been heretofore used are not constructed to prevent this. 30 My invention also tends to prevent dust and cinders from entering the car through the ventilator.

The invention is illustrated in the accompanying drawings, wherein—

Figure 1 is a front elevation of a ventilator of known type provided with the improved feature constituting part of my invention; Fig. 2, a view, in perspective, of the attachment shown in Fig. 1; Fig. 3, a sectional view of Fig. 1; Fig. 4, a fragmentary cross sectional view of the top of a railway car showing the form of ventilator illustrated in Figs. 1 to 3 inclusive, attached to 35 a clear story; Fig. 5, a view similar to Fig. 4 showing a ventilator of the same general type as that shown in the preceding figures but improved in respect to the form of the cowl or hood; Fig. 6, a side elevation of an 40 improved form of ventilators, the parts being in section, and Fig. 7 is a front elevation of the same.

Like characters of reference indicate like 45 parts in the several figures of the drawings.

Referring to the drawings, 25 (Figs. 4 and 5) designates the body of the car, 26 the deck and 27 the clear story, the latter being provided with the usual windows 28.

In Figs. 1 to 4 inclusive I have shown a 50 ventilator comprising a hood or cowl 29 formed with flanges 30 for attachment to

the clear story of the car. The cowl, tapered from back to front, is closed on the top and sides and formed with an opening at the front and under side. Ventilators consisting of cowls or hoods of this configuration have been used for ventilating railway cars prior to my invention. When attached to the side of a car, for example, over one of the clear story windows or ventilating openings, the movement of the car produces a draft over the opening in the cowl which sucks the foul air out of the car. One objection to a ventilator of this sort is that when the car is standing still, if the wind 60 happens to be blowing in a direction toward the opening of the ventilator, it will enter the car through the ventilator producing uncomfortable drafts and perhaps reducing the temperature of the car over much if the weather is cold. My invention provides an improvement which in a very great measure obviates this objection without in any way affecting the operation of the ventilator when the car is in motion. The improvement consists in arranging a deflecting element in front of the discharging opening of the ventilator of such a character as to prevent a direct back draft of cold air through the ventilator without, however, 65 closing the opening. The form and construction of the deflecting element may be varied. I prefer to construct the deflecting element substantially as shown in Figs. 1 to 4, in which 31 designates a plate formed 70 with a plurality of transverse slots 32 and with a plurality of lips or flanges 33 extending downwardly over the slots. For convenient attachment to the cowl the plate 30 is formed with flanges 34 on the sides and a 75 flange 35 at the upper outer end. Bolts 36, or other suitable means, may be employed for securing the deflecting plate to the cowl. It is not essential that the deflecting plate 80 should be made separate from the cowl. If the plates are so made they may be attached to ventilators of the sort described which have been installed without being provided 85 with the deflecting plates over their discharge opening.

It will be seen that the deflecting element above described effectively prevents the wind from blowing into the car through the ventilator when the car is at a standstill. It does not in any way affect the operation 90 of the ventilator when the car is in motion. On the contrary, it tends to improve that 95 100 105 110

operation by preventing any eddying of the draft around the edges of the opening.

As stated, the cowls of ventilators of the type here concerned are usually tapered from back to front in the manner shown in Figs. 1 to 4 inclusive, the purpose of this being to narrow the opening as much as possible and particularly at the nose or forward end of the ventilator so as to so far as possible prevent back drafts of air into the car. Obviously however, this tapering of the cowl diminishes the strength of the draft induced by the movement of the car and proportionately diminishes the force of the suction by means of which the foul air is withdrawn from the car. By providing a deflecting element over the discharge opening of the ventilator so that the danger of the wind blowing into the car is eliminated it is possible to change the contour of the cowl so as to get a stronger suction. With the discharge opening protected by a deflecting element such as that above described the size and contour of the opening become unimportant.

In Figs. 5 to 7 inclusive I have shown an improved form of cowl which is much more effective as a ventilator than the form shown in the preceding figures. The cowl consists of a top 37, which is of substantially uniform width from back to front, sides 38, which are preferably concave, and attaching flanges 38^a. The opening in the front and under side is provided with a deflecting plate or element 39 which may be made on the same general principle as the deflecting plate shown in Fig. 2. Additionally I prefer to provide the cowl with the upstanding and outstanding wings 40 at the intersection between the top and sides. The purpose of the wings is to increase the amount of air which is intercepted by the ventilator when the car is in motion and thereby increase the draft over the discharge opening. With the cowl of the ventilator so formed the air is pocketed between the sides of the car and a draft produced over the edge

of the discharge opening which has a much greater velocity than would be the case if the side of the cowl against which the air impinges were oblique to the direction of the movement of the car, as in the tapered form of cowl, instead of standing at right angles thereto.

While I have illustrated my invention in certain preferred embodiments it will be understood that further modifications might be made without departure from the invention. Therefore I do not limit myself to the exact forms and construction shown and described, except as the same are made specific limitations in certain of the claims; my purpose being to claim both broadly and narrowly whatever patentable novelty the invention may possess in view of the state of the art.

I claim:

1. A ventilator for a railway car, or the like, consisting of a cowl having an imperforate top, imperforate lateral air-collecting faces extending inwardly and downwardly from the top, an inner side adapted to communicate with the interior of the car, and an open front and under side provided with a slatted structure comprising a plurality of parallel transversely extending downwardly projecting slats.

2. A ventilator for a railway car, or the like, consisting of a cowl having an imperforate top, imperforate lateral air-collecting faces extending inwardly and downwardly from the top, an inner side adapted to communicate with the interior of the car, an open front and under side provided with a slatted structure comprising a plurality of parallel transversely extending downwardly projecting slats, and wings projecting obliquely upwardly and outwardly from the intersections of the top and lateral faces.

EGBERT H. GOLD.
